Horace Hall, Rutherford Township, Ohio

Collins Patent

In the State aforesaid to a Miss Collins Patent and making part of the same
containing a description in the words of the said Horace Hall himself of his
Improvement in Thatching Stays or Binding Beams.

It is known that I Horace Hall of Rutherford Township, Clermont County and
State of Ohio have made an improvement in thatching Stays or Binding Beams
which is described as follows. 1° The Beam. This is made by tenoning and
mortising together two side pieces about ten feet long; the end pieces about the
foot long; & stand in legs about thirty inches high.

2° The carriage is of the same length and width of the beam. The binding
and carriage & the same as that is common are but the said instead of being
regulated by a spring, as is present, is done by a screw called the binding screw
having a catch or spring rod working to the threads of the screw at the end
& the carriage which carries forward the carriage. The end of this screw
is supported and works in an upright at the end of the frame, and the other
end is a foot having a cog wheel on its end which meshes and works into a
cog wheel on the fly. When the carriage is to be moved back the spring rod
is disengaged from the screw, & instead of the spring rod a small screw
placed in the end of the carriage into which the main screw may work, to be
inserted the same proper.

Operation. The rods after being cut and shaped are put in between the side
inside pieces by hand, and the hands while giving the tenoning motion are
marked by the foot in the usual way; and the beam which carries the carriage
regulates the winding and binding up of the strand, as herein with the utmost
economy. On each motion of the foot a step is put in by the hand, and the
beam is thus made upon a round in the proper place by the operation of the hands.

The improvement which I claim as my invention consists in the joining beam
and beam described in regulating the winding and binding up instead of the spring rod being
common use, and in the substitution of my invention instead of the beam and binding of the same, as per
the former Patent of Washington's Patent No. 111.
